UNITED STATES PATENT OFFICE.

MERRITT MILLER, OF CANTON, OHIO.

ALUMINUM ROLLING PIN.

Application filed November 22, 1921. Serial No. 516,942.

To all whom it may concern:

Be it known that I, MERRITT MILLER, a citizen of the United States, residing at Canton, in the county of Stark and State of Ohio, have invented a new and useful Aluminum Rolling Pin, of which the following is a specification.

This invention relates to new and useful improvements in rolling pins and more particularly to a rolling pin formed of aluminum, and has for its objects to provide a rolling pin which will be light in weight, simple and inexpensive in construction and sanitary in use.

15 The above and other objects may be attained by providing a construction such as is illustrated in the accompanying drawings in which—

Figure 1 is a side elevation of a rolling pin embodying the invention;

Fig. 2, a longitudinal, sectional view through the same; and

Fig. 3, a detached perspective view of one of the end caps.

25 Similar numerals of reference indicate corresponding parts throughout the drawing.

The body portion of the rolling pin comprises a cylindrical tube 1 closed at its ends by means of end caps 2 which are preferably stamped from sheet aluminum, being provided with the inwardly disposed, annular flanges 3 arranged to be inserted into the open ends of the aluminum tube 1, said end caps being shouldered as at 4 to abut 30 the ends of the aluminum tube.

The end caps are preferably slightly convexed as shown at 5, being provided with the central, concentric depressions or sockets 6, a concentric opening 7 being formed 35 through each end cap in order to receive the rod 8 which is of greater length than the tube 1 and extends entirely through the longitudinal center thereof, the ends protruding beyond each end cap.

The handles 9 which may be of wood, 45 hard rubber or the like, are each provided with a central bore and journaled upon the end portions of the rod 8 which protrude beyond the ends of the body of the pin, each of these handles being provided with the 50 annular shoulder 10 received within the depression 6 of the adjacent end cap.

The extremities of the rod 8 are threaded as shown at 11 to receive the nuts 12 which are preferably formed of aluminum and are provided with the threaded sockets 13 entirely enclosing the end portions of the rod. The handles are thus held in position upon the rod, the shouldered portions 10 thereof being journaled within the annular recess 60 60 of the end caps, relieving the openings 7 in the end caps from considerable wear when the rolling pin is operated.

As is well understood, aluminum is very 65 easy to clean and to keep in a cleaned condition, and as it is susceptible to a very high polish, the possibility of dough sticking to the rolling pin is eliminated. By forming the handles 9 of hard rubber or similar material, a very sanitary rolling pin is produced, and one which may be placed in boiling water if necessary for the purpose of cleansing.

I claim:—

A rolling pin including an open ended 75 aluminum tube, end caps provided with reduced annular flanges received within the ends of the tube, each end cap having a concentric, annular socket provided with a concentric opening, a rod located through 80 said openings and protruding beyond opposite ends of the tube, handles journaled upon the end portions of the rod and extending into said annular sockets and nuts upon the extremities of the rod. 65

In testimony that I claim the above, I have hereunto subscribed my name.

MERRITT MILLER.
